Patented Dec. 7, 1926.

UNITED STATES PATENT OFFICE.

LAWRENCE A. GROLEMUND, OF CHARLESTON, WEST VIRGINIA, ASSIGNOR TO THE LIEBEY-OWENS SHEET GLASS COMPANY, OF TOLEDO, OHIO, A CORPORATION OF OHIO.

DRAWING FLAT SHEET GLASS.

Application filed September 27, 1923. Serial No. 665,051.

This invention relates to improvements in the art of drawing flat sheet glass, and more especially to an improved method of and apparatus for regulating the temperature of individual transverse portions of the drawn sheet at an intermediate stage of the sheet formation.

The invention is more particularly applied to controlling the temperature of the sheet while it is still in a semi-plastic condition and is being deflected from a vertical to a horizontal plane prior to the flattening process. In the Colburn process of drawing flat sheet glass, as set forth for example in the patent to I. W. Colburn, 1,248,809, granted Dec. 4, 1917, a sheet of glass is drawn upwardly from a pool of molten glass, and while substantially set in sheet form, but still somewhat plastic, is deflected about a bending roller into the horizontal plane where it is carried away through suitable drawing and flattening mechanism into the leir. It is essential that the temperature of the glass sheet and of the bending roller, be very accurately controlled, since if the sheet and roller are too hot, the sheet will stick to the roller and be injured thereby, whereas if the roller or sheet are too cold the bending process cannot be carried out without breaking the sheet. The roller is ordinarily somewhat cooled internally by passing a cooling fluid, usually air, therethrough. A water-cooler is positioned below the roller and adjacent the glass sheet, this cooler serving to cool the surfaces of the sheet and roller before they contact with one another, and also serving to shield the lower surface of the roller from the heated air currents passing up from the molten mass of glass from which the sheet is drawn. The sheet, while still sufficiently plastic to be bent about the roller, becomes so chilled during the bending process that it is necessary to reheat the sheet somewhat as it leaves the roller in order that it may be drawn away therefrom in flat form. For this purpose a pipe burner, consisting of a longitudinal series of separate flames or burners arranged transversely of the sheet is so positioned that the flames play upon the sheet just before it leaves the surface of the bending roller.

Due to various causes, such as changeable air currents passing through the machine,

the internal structure of the bending member and sheet, and the difficulty of accurately controlling the heating and cooling mechanism, cold or hot spots sometimes develop in the bending member or sheet, or both, which adversely affect the quality and evenness of the finished glass sheet.

The aim of the present invention is to separately control the temperature of the roller and glass sheet at different local points longitudinally of the roller and transversely of the sheet, so that such hot or cold spots may be counteracted and eliminated.

One object of the invention is to provide a sectional auxiliary cooler for the bending member comprising a series of separately controllable cooling chambers.

Another object is to provide a heat insulating shield for substantially all of those portions of the roller not in contact with the glass sheet.

Another object is to provide a reheating burner for the sheet, which burner is comprised of a series of independently regulable sections, whereby the application of heat to the sheet may be controlled along with or separately from the application of cooling means to the roller as above noted.

Other objects and advantages of the invention will become more apparent from the following detailed description of one approved form of the apparatus used.

In the accompanying drawings:

Fig. 1 is a longitudinal vertical section through a portion of the sheet drawing mechanism and the temperature regulating apparatus. The section is taken near the adjacent end of the bending roller as viewed in this figure.

Fig. 2 is an end elevation of the cooling and heating apparatus, the bending roller being shown in section in a plane nearer the observer than the plane of Fig. 1.

Fig. 3 is an inner plan view of the insulating shield and auxiliary cooler, parts being broken away. The view is taken looking from the position that would be occupied by the bending roller.

Fig. 4 is an elevation also looking from the position of the bending roller at the heating apparatus.

The glass sheet 1 is drawn upwardly from the pool of molten glass 2 in receptacle 3, between the surface coolers 4 and the edge-

forming rollers 5, all as specifically disclosed in the Colburn patent noted above. After the sheet has been drawn to substantially its final form, but is still somewhat plastic, it is deflected about the cooled bending roller 6 into a horizontal plane wherein it is drawn away over supporting rolls 7 and 8 into a suitable drawing and flattening mechanism not here shown. The bending roller 6 is cooled by passing a cooling fluid, preferably air, therethrough, as in previous practice.

Approximately 90° of the outer surface of roller 6 will always be in contact with the glass sheet 1, but the other 270° is ordinarily exposed to the air, and is subject to variable air currents of different temperatures, as well as dust and other materials that may be deposited on the roller from these air currents.

To protect the roller as far as possible from these conditions, the shield 9, preferably of arcuate contour with its center of arc lying substantially in the axis of the roller, is positioned beneath the roller with its edges terminating closely adjacent the vertical and horizontal runs of the glass sheet 1. The arcuate portion of this shield is preferably composed of two separated metal shells, the chamber formed therebetween being filled with asbestos or other suitable insulating material. The inner wall 10 of the shield is spaced some little distance from the outer surface of roller 6, but adjacent the ends of the shield, and the ends of the glass-carrying surface of roller 6, vertical partitions 11 extend from the arcuate portion of the shield closely adjacent to the roller surface so as to form a substantially enclosed chamber about all of the glass-carrying portion of the roller not in contact at that time with the glass sheet. Preferably formed as a unit with this shield at the edge thereof adjacent the vertical run of the glass sheet 1, is a water-carrying chamber 12 extending longitudinally of the shield and transversely of sheet 1. A cooling fluid is fed to and through this chamber as in ordinary practice, and this shield serves the purpose of partially chilling the inner surface of the sheet before its contact with the bending roller, as in the form of apparatus previously used.

An auxiliary cooler 13 is carried by shield 9 and positioned between the inner wall 10 of the shield and the adjacent surface of roller 6. This auxiliary cooler is composed of a longitudinal series of separate chambers 14, here shown as six in number, although any suitable number may be used. Individual inlet pipes 15 and outlet pipes 16, extend to and from each separate chamber 14, to convey the cooling water or other fluid to the chamber and discharge it therefrom. Preferably these inlet and outlet pipes may be grouped as shown in the draw-

ings, and positioned within the body of the shield 9, whereby they will be protected against temperature changes by the surrounding asbestos packing. Each inlet pipe 15 is provided with an individual controlling valve 17, these valves preferably being grouped at one end of the machine, as shown in Fig. 2. By separately manipulating these valves, the flow of cooling fluid through any one or all of the chambers 14 may be selectively regulated.

The reheating apparatus 18 comprises, as has been the usual practice, a tubular pipe or chamber provided with a longitudinal row of closely adjacent burner holes, whereby a series of separate flames are projected in a line against the sheet surface so as to substantially form a continuous sheet or blanket of heating flame. In this new form of burner, the pipe 18 is divided by a series of separate internal partitions 19 into a number of individual gas-holding chambers, here shown as six in number, although any suitable number may be used. A separate inlet pipe 20 supplies gas to each chamber. At one end of the machine, preferably the same end where valve 17 of the cooler is located, each of the gas-supplying pipes 20 is provided with a controlling valve 21. As shown in Fig. 2, the supply pipes 20 may all terminate in a single manifold 22 supplied from a main gas pipe 23. By suitably regulating the valves 21, the supply of gas to any of the separate chambers in pipe 18 may be limited or entirely cut off so as to control the intensity or eliminate each individual group of flames at different transverse intervals across the sheet surface.

In normal operation, the cooler 12 will always be used, and ordinarily the entire series of reheating burners will be in operation across the width of the sheet. The series of auxiliary coolers 13 may or may not be normally necessary according to the design of the apparatus. This will depend on the capacity of cooler 12 to sufficiently chill the surfaces of the sheet and bending member. If a hot spot develops in the roller 6 or in the sheet 1, or both, this may be counteracted by applying cooling fluid to that section or sections of cooler 13 nearest to this overheated portion of the roller. At the same time application of heat from burner 18 may be restricted or entirely cut off at the corresponding portions of sheet 1. Conversely if one portion of roller 6 or sheet 1 becomes too cool, the adjacent portions of the cooler 13 may be cut out by stopping the flow of cooling fluid therethrough, and the intensity of the reheating burner 18 at that point may be increased. As shown in Fig. 2, the two end sections of cooler 13 are out of service, the supply valves 17 being closed. One of the inner sections of the reheating burner 18 is shut off, as indicated by the

closed valve 21 at the upper right of Fig. 2. It will be seen that with the combined application of these locally controllable heating and cooling members, the temperature of different transverse areas of the sheet may be quite accurately regulated and variable disturbing factors which would ordinarily cause inequalities in the sheet may be largely overcome. The protecting shield around those portions of the bending roller which would ordinarily be exposed to air currents also greatly assists in maintaining even temperature conditions during the bending process.

15 Claims:

1. In apparatus for producing sheet glass, a cooler positioned transversely of the glass sheet, and comprising a longitudinal series of separately regulatable sections.
2. In apparatus for producing sheet glass, a cooler positioned transversely of the glass sheet, and comprising a longitudinally arranged series of separate chambers, and means for independently and selectively flowing a cooling fluid through each chamber.
3. In apparatus for producing sheet glass, a cooler positioned transversely of the glass sheet, and comprising a longitudinally arranged series of separate chambers, individual inlet and outlet pipes leading to each chamber, and means accessible from outside the machine for controlling the flow of cooling fluid to each chamber.
4. The combination with a sheet glass drawing apparatus, comprising a bending member about which the sheet is deflected from one plane to another, of means for controlling the temperature of the bending member and the glass sheet, comprising a cooler formed of separately regulatable sections positioned adjacent the bending member.
5. The combination with a sheet glass drawing apparatus, comprising a bending member about which the sheet is deflected from one plane to another, of means for controlling the temperature of the bending member and the glass sheet, comprising a cooler formed of a series of separate chambers arranged longitudinally of and adjacent the bending member, and connections for independently flowing a cooling fluid through each of the chambers.
6. The combination with a sheet glass drawing apparatus, comprising a bending member about which the sheet is deflected from one plane to another, of means for controlling the temperature of the bending member and the glass sheet, comprising a cooler formed of a series of separate chambers arranged longitudinally of and adjacent the bending member, individual inlet and outlet pipes for a cooling fluid leading to each chamber, and means accessible from

outside the machine for controlling the flow of fluid through each of the chambers.

7. The combination with a sheet glass drawing apparatus, comprising a bending member about which the sheet is deflected from one plane to another, of a shield lined with heat insulating material, enclosing substantially that portion of the bending member not in contact with the glass sheet.

8. The combination with a sheet glass drawing apparatus, comprising a bending member about which the sheet is deflected from one plane to another, of a shield lined with heat insulating material, enclosing substantially that portion of the bending member not in contact with the glass sheet, a sectional cooler positioned between the shield and member, and means for separately controlling the several cooler sections.

9. The combination with a sheet glass drawing apparatus, comprising a bending member about which the sheet is deflected from one plane to another, of a shield lined with heat insulating material, enclosing substantially that portion of the bending member not in contact with the glass sheet, a cooler comprising a series of separate chambers positioned between the shield and member, and separate connections for feeding a cooling fluid to each chamber, the connections being protected by the insulating material of the shield.

10. In apparatus for producing sheet glass, a heater positioned adjacent and transversely of the glass sheet, comprising a longitudinal series of burners, and means for separately feeding and controlling different groups of these burners.

11. In apparatus for producing sheet glass, a heater positioned adjacent and transversely of the glass sheet, comprising a tubular member having a longitudinal row of burner outlets, the tubular member being interiorly divided into a series of separate chambers, and means for independently feeding gas to each chamber.

12. The combination with a sheet glass drawing apparatus, comprising a bending member about which the sheet is deflected from one plane to another, of a heater for controlling the temperature of the sheet as it leaves the bending member, the heater being formed of a series of separately controlled sections.

13. The combination with a sheet glass drawing apparatus, comprising a bending member about which the sheet is deflected from one plane to another, of a heater for controlling the temperature of the sheet as it leaves the bending member, the heater comprising a longitudinal series of burners arranged transversely of the glass sheet, and means for independently feeding and controlling separate groups of these burners.

14. The combination with a sheet glass

drawing apparatus, comprising a bending member about which the sheet is deflected from one plane to another, of means for controlling the temperature of the bending member and the glass sheet, comprising a cooling member and a heating member arranged transversely of and adjacent the bending member and sheet, both the cooler and the heater being formed of a series of separate chambers, and means for independently and selectively feeding the cooling or heating fluid to each chamber.

5 15. The combination with a sheet glass drawing apparatus, comprising a bending member about which the sheet is deflected from one plane to another, of means for controlling the temperature of the bending member and the glass sheet, comprising a cooling member and a heating member arranged transversely of and adjacent the

10 independently regulatable sections.

15. The combination with a sheet glass drawing apparatus, comprising a bending member about which the sheet is deflected from one plane to another, of means for

controlling the temperature of the bending member and the glass sheet, comprising a cooling member and a heating member arranged transversely of and adjacent the

bending member and sheet, both the cooler and the heater being formed of a series of 20 separate chambers, and means for independently and selectively feeding the cooling or heating fluid to each chamber.

16. The process of regulating the temperature of a glass sheet, and a member 25 about which the sheet may be deflected from one plane to another, which consists in creating heat absorbing zones in proximity to the deflecting member, and then regulating the temperature of each zone in a manner to make uniform the temperature of said deflecting member.

Signed at Charleston, in the county of Kanawha and State of West Virginia, this 17th day of September, 1923.

LAWRENCE A. GROLEMUND.
